HOLDER FOR PHONOGRAPH RECORDS

Samuel Beder, New York, N. Y.

Application August 20, 1941, Serial No. 407,569

10 Claims. (Cl. 312—12)

This invention relates to holders for phonograph records.

An object of this invention is to provide a holder of the character described, in which the phonograph record envelopes are slidably mounted so that they may be selectively moved forward to project from the holder sufficiently to permit removal of a desired record, means being furthermore provided to permit removal of any or all of the envelopes for replacement of torn envelopes.

Yet a further object of this invention is to provide a holder of the character described, so constructed that a number of such holders may be readily mounted within any cabinet, for example, a phonograph cabinet.

Still another object of this invention is to provide a compact, neat and durable holder of the character described, supporting a relatively large number of phonograph records, which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown various possible illustrative embodiments of this invention,

Fig. 1 is a perspective view of a phonograph record holder embodying the invention shown, for the purpose of illustration, as a portable case for records;

Fig. 2 is a cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 2;

Fig. 5 is a partial view similar to Fig. 1, and showing one of the envelopes pulled forward to permit removal of the phonograph record;

Fig. 6 is a side elevational view of one of the phonograph envelopes mounted on its hanger;

Fig. 7 is a partial perspective view of a cabinet and a phonograph record holder embodying the invention, and illustrating a modified construction;

Fig. 8 is a perspective view of a plurality of

phonograph record envelopes mounted on a hanger;

Fig. 9 is a top plan view of a hanger;

Fig. 10 is a cross-sectional view taken on line 10—10 of Fig. 9; and

Fig. 11 is a side elevational view taken on line 11—11 of Fig. 9.

Referring now in detail to the drawings, 10 designates a phonograph record holder embodying the invention. The same comprises a case 11 having a bottom wall 12, a top wall 13, side walls 14 and a rear wall 15. The case is open at the front. The front of the case may be closed by a hinged door 17. The case may furthermore be provided with a strap handle 18 at the top, whereby to permit the holder to be carried around, thus making the same a portable phonograph holder.

The inner surfaces of side walls 14 of the case are formed, adjacent the upper ends thereof, with similar, aligned, horizontal rail grooves 22 extending to the front open end of the case. The grooves 22 are widened or enlarged downwardly, as at 23 at the rear ends thereof. Thus, the rear portions 23 of the grooves 22 are of greater vertical height or width than the front ends thereof.

Supported on and between the side walls 14 of the case is a hanger 25 for phonograph record envelopes 26. The holder 25 may be made of metal wire, or of any other suitable material and is substantially rectangular. The same has parallel side portions 28 and parallel front and end portions 29. The length of the side portions 28 is substantially equal to the lengths of the widened portions 23 of grooves 22, and said portions of the hanger 25 rest within the groove portions 23 when the hanger is pushed back in grooves 22. The front and rear portions 29 are formed with flat, parallel, transverse grooves 30 in the upper sides thereof, for the purpose hereinafter appearing.

The width of groove 22 is sufficient to permit the hanger to be slidably moved through said grooves. Thus, the hanger 25 may be inserted through the grooves 22, pushed rearwardly and will then drop into groove portions 23.

It will be noted that the shoulders 23a at the forward ends of the groove portions 23 serve as stops to prevent the hanger from accidentally sliding forwardly out of the case.

A plurality of record envelopes 26 are slidably mounted on the hanger 25. The envelopes 26 are formed adjacent the upper edges thereof with horizontal registering slots 32, longer than the

side portions 28 of the hanger 25. Portions 29 of hanger 25 extend transversely through the registering slots 32 and the upper edges 35 of said slots engage within the slots 30 of the hanger, so that the envelopes will not shift sideways.

It will now be understood that each envelope may be slidably moved forwardly to project through the front open end of the case 11, to permit removal of the record within said envelope. The envelopes may be numbered in series as by tabs 36. Should any envelopes be torn or need replacement, the entire hanger 25 together with the envelopes 26 may be removed from the case 11, to permit replacement of the envelopes. To remove the hanger, it is lifted in groove portions 23 to clear the shoulders at the front ends of said groove portions. The hanger together with the envelopes may then be reinserted into the case.

In Fig. 7 there is shown a cabinet 40, such as 20 a phonograph cabinet or a radio cabinet. Mounted within the cabinet 40 are one or more phonograph record holders 10a, embodying the invention, and illustrating a modified form thereof. The holders 10a each comprise a member 41 made of wire. Each member 41 comprises a bottom rectangular member 42 made of wire and comprising parallel side portions 43 and parallel end portions 44. The end portions 44 may each be provided with a pair of intermediate loops 45 to receive screws 46 or other fastening members for fastening member 41 to the bottom wall 48 of the cabinet.

Welded or otherwise attached to each side portion 43 of member 42, is a vertical side member 50. Members 50 are parallel to each other, and only one thereof will be described. Each member 50 may be made of a single piece of wire and comprises vertical, parallel end portions 51, from the upper ends of which there extend inwardly short horizontal portions 52. Extending inwardly from the lower ends of portions 51 are horizontal, aligned portions 53 contacting the side portions 43 of member 42. Extending upwardly from the inner ends of portions 53 are vertical portions 54, from which there extends inwardly aligned, horizontal portions 55 aligned with the wire end portions 52. Extending downwardly from the inner ends of portions 55 are vertical portions 56 interconnected by a bottom horizontal portion 57 likewise contacting one of the side portions 43 of member 42.

Mounted on and attached to the upper ends of members 50, is a rectangular member 60 made of wire, and having parallel side portions 61 contacting the portions 52 and 55 of members 50, and end portions 62 interconnecting the side portions 61. Members 60 and 42 are in alignment and in horizontal planes as shown in the drawings. Member 60 may be attached to the upper ends of members 50 likewise by welding or in any other suitable manner.

Fixed to the inner sides of members 50 adjacent the upper ends thereof are a pair of similar aligned parallel members or rails 70, each made of a single piece of wire. Each member 70 comprises aligned end portions 71 interconnected by a depressed horizontal portion 72 disposed at a level lower than portion 71. The portions 71 of each member 70 contact and are fixed to portions 51 and 54 of member 50, whereas, the depressed portion 72 contacts and is attached to portions 56 of member 50.

The hanger 25 may be inserted between mem-

bers 50 and above members 70, and pushed back until it drops onto the depressed portions 72 of member 70. The envelopes 26 are thus slidably supported on the hanger, which in turn is mounted on member 41.

It will now be understood that any suitable number of members 10a may be mounted in any suitable cabinet space.

It will thus be seen that there is provided a 10 device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a support, a hanger, recessed means on said support to receive and support said hanger against sliding movement, means 25 on said support to slidably support said hanger upon lifting said hanger out of said receiving means to permit said hanger to be slidably moved off said support and a plurality of envelopes having registering slots receiving said hanger, said envelopes being wholly supported by said hanger, the length of said slots being greater than the length of said hanger.

2. In combination, a support having parallel portions, a hanger mounted on and between said parallel portions and adapted to be removed therefrom, means on said support to hold the hanger against sliding movement, and a plurality of phonograph record envelopes disposed between said portions and having means to slidably engage said hanger, said envelopes being adapted to be selectively pulled forwardly on said hanger, and means on said hanger to keep the envelopes in spaced parallel relative positions.

3. In combination, a case having side walls, 45 said side walls being formed on the inner surfaces thereof and adjacent the upper ends thereof with horizontal grooves, the rear portions of said grooves being widened downwardly, a hanger having side portions, and portions interconnecting said side portions, said side portions being received within the widened portions of said grooves, and being adapted to be raised and moved through the narrow portions of said grooves, out of the case, and a plurality of phonograph record 55 envelopes having registering slots, the interconnecting portions of said hangers extending transversely through said registering slots, said registering slots being longer than the side portions of said hangers.

4. In combination, a support, means to attach said support to a cabinet, said support having parallel vertical portions, a hanger between said parallel portions, said hanger being capable of being slidably inserted between said portions and slidably removed therefrom, means on said parallel portions to retain said hanger against forward sliding movement, after said hanger has been inserted between said parallel portions a predetermined distance, a plurality of phonograph record envelopes having registering slots, said hanger passing through said slots and permitting said phonograph record envelopes to be selectively slidably moved forwardly on the hanger.

5. A member comprising top and bottom rectangular frames, and a pair of parallel, verti-

cal side frames interconnecting the sides of said top and bottom frames, and rails on the inner sides of the side frames, said rails having intermediate depressed portions, a rectangular hanger having side portions and interconnecting portions, the side portions of said hanger being received on the depressed portions of said rails.

6. A member comprising top and bottom rectangular frames, and a pair of parallel, vertical side frames interconnecting the sides of said top and bottom frames, rails on the inner sides of the side frames, said rails having intermediate depressed portions, a rectangular hanger having side portions and interconnecting portions, the side portions of said hanger being received on the depressed portions of said rails, and a plurality of phonograph record envelopes having registering slots, the interconnecting portions of said hanger passing transversely through said slots.

7. A member comprising top and bottom rectangular frames, and a pair of parallel, vertical side frames interconnecting the sides of said top and bottom frames, rails on the inner sides of the side frames, said rails having intermediate depressed portions, a rectangular hanger having side portions and interconnecting portions, the side portions of said hanger being received on the depressed portions of said rails, and a plurality of phonograph record envelopes having registering slots, the interconnecting portions of said hanger passing transversely through said slots, said slots being longer than the side portions of said hanger, whereby said envelopes may be slidably moved on said hanger.

8. A member comprising top and bottom rectangular frames, and a pair of parallel, vertical side frames interconnecting the sides of said top and bottom frames, rails on the inner sides of the side frames, said rails having intermediate de-

pressed portions, a rectangular hanger having side portions and interconnecting portions, the side portions of said hanger being received on the depressed portions of said rails, and a plurality of phonograph record envelopes having registering slots, the interconnecting portions of said hanger passing transversely through said slots, said slots being longer than the side portions of said hanger, whereby said envelopes may be slidably moved on said hanger, said bottom frame being formed with portions to receive fastening means for fastening the same to the cabinet.

9. In combination, a member, a hanger removably mounted thereon, and a plurality of phonograph record envelopes having registering slots slidably receiving said hanger, said hanger comprising a pair of parallel spaced portions disposed transversely of said envelopes and passing through said slots, and said envelopes being wholly supported by said portions of said hanger, the length of said slots being greater than the distance between said parallel portions of said hanger, said portions of said hanger having grooves to engage said envelopes.

10. In combination, a member adapted to receive a plurality of phonograph record envelopes inserted therein in vertical positions, a horizontal hanger removably mounted within said member, said member having means to retain said hanger against sliding movement, but permitting said hanger to be lifted off said retaining means and drawn forwardly out of said member, said envelopes being formed with registering slots longer than the hanger, portions of said hanger extending through said registering slots, and said envelopes being wholly supported on said hanger, and said envelopes being individually movable forwardly on said hanger.

SAMUEL BEDER.
